UNITED STATES PATENT OFFICE.

HUGH P. McMILLAN, OF BALTIMORE, MARYLAND, ASSIGNOR TO SAMUEL M. DELL & CO., INC., OF BALTIMORE, MARYLAND, A CORPORATION OF MARYLAND.

METHOD OF MANUFACTURING BRUSHES.

Application filed April 23, 1926. Serial No. 104,154.

This invention relates in general to brushes and their manufacture, and one of the objects of the invention is to provide a new and greatly simplified method of manufacturing certain types of brushes, particularly those brushes in which the bristles are secured in vulcanized rubber.

One of the particular objects of the invention is to eliminate the present steps of removing the plug used in the formation of the brush and fitting the handle in the space occupied by the plug; and in place of those steps to allow the plug to remain in the brush and secure the handle directly to the plug.

Another of the particular objects of the invention is to avoid the necessity of an accurate centering of the plug in the knot; this being effected by forming the handle socket in the plug after the brush has been otherwise completed.

Another object of the invention is to provide a method by which brushes of the type described herein may be manufactured at a great saving of time, labor, and material.

Prior to the invention of the method to be described herein, brushes of the type covered by the present invention have been manufactured by a method which was not only slow and expensive, but also resulted in the loss of a great many brushes by loosening the fiber thereof. The method which has been generally employed is well illustrated in the patent to Potter No. 928,401.

In accordance with the method in common use the bristles are first formed into a bunch; one end of the bunch of bristles is then dipped into a rubber solution to the desired extent to form the knot. The opposite sides of the bunch are then separated and a plug is inserted in the opening. After the plug has been placed in the knot the bunch of bristles is placed in a drying oven to effect to some extent the hardening of the rubber solution; the knot end of the bristles containing the wooden or metal plug is then placed on a heated table until the vulcanization is complete. The plug is then loosened and knocked out; and the handle is inserted

in the space that was occupied by the plug. 50 The removal of the plug requires considerable time; but more important than that is the fact that the bristles often become loosened during the removal of the plug and when that happens the brush is a total loss. 55 In accordance with the present invention the plug is placed in the knot in the manner described above; but instead of removing it later in the process it remains permanently in the knot.

The idea of permanently mounting the plug in the knot has previously been suggested in the patent to Hugh P. McMillan, No. 1,009,082, November 21, 1911, but in the structure disclosed there a metal plug was 65 employed and for various reasons the structure has been found to be impracticable. It is obvious that in a structure such as shown in McMillan No. 1,009,082, the socket for receiving the handle must be formed in the 70 plug before the plug is inserted in the knot and this being true, it follows that the plug must be very accurately centered with respect to the knot, for otherwise an unbalanced brush would result.

In the present invention applicant employs a wooden plug and he inserts it in the knot without any attempt whatever to accurately center it with respect to the knot; and then after the brush has been formed a 80 socket to receive the handle is made in the plug; this socket being centered not with respect to the plug but with respect to the brush.

It will be clearly understood, from the 85 foregoing description, that the material features of the invention reside in permanently mounting a wooden plug in the knot, thereby avoiding the necessity of removing the plug before the handle is inserted; and in 90 providing the handle receiving socket in the plug after the brush has been otherwise completed.

It is believed that the invention will be clearly understood from the following detailed description taken in connection with the accompanying drawing; in which,

Figure 1 is a perspective view of the

brush, before the handle receiving socket is provided in the plug.

Figure 2 is a fragmentary perspective view of the brush with the handle receiving socket provided in the plug, and the handle ready to be mounted in the socket; and,

Figure 3 is a vertical sectional view of the brush, and showing the handle attached thereto.

10 Referring to the drawings more in detail numeral 1 indicates the bristles. These bristles are arranged in the desired shape by any preferred method, and are then treated with the rubber solution, in the usual manner. The ends of the bristles are thus formed into what is termed a knot, referred to by numeral 2. The plug is indicated by numeral 3; and this plug, in accordance with the present invention, is now inserted in the 20 knot of bristles; and the metallic band 4 is secured in place. It will be understood that the plug 3 when inserted in the knot, has not been provided with the handle receiving socket but has a perfectly plain upper surface, as illustrated in Figure 1.

The rubber must now be vulcanized, and to accomplish this vulcanization it is only necessary to stand the knot on a heated table for the required period of time. An inspection of the drawing will show that the plug, the knot, and the band, are all in the same plane, and consequently the knot can be applied directly to the table.

30 After the vulcanization has been completed the next step is to provide the handle receiving socket 5 in the plug 3. It will be obvious to those skilled in the art that a great deal of time would be required to accurately center a plug with respect to the knot; and 40 as previously stated herein one of the material features of the present invention resides in the elimination of the necessity of centering the plug with respect to the knot. In accordance with the present invention the plug 45 is placed in the knot roughly in the center thereof, but no attempt is made to accurately center it and it is immaterial in the present invention whether or not it is accurately centered. After the brush has been formed 50 as hereinbefore described, the center of the brush is determined and the handle receiving socket 5 is made in the plug. Obviously no difficulty is encountered in locating the center of the brush and in making the socket at the center thereof, but the great difficulty would be in accurately centering the plug with respect to the knot.

60 It will be understood from the foregoing description that if by any chance the plug should be accurately centered in the knot then the handle receiving socket would be made in the center of the plug, but in most cases the plug would not by chance be positioned accurately in the center of the knot, and in all of such cases the handle receiving

socket would not be in the center of the plug, but might be off center in any direction, though it would always be in the center of the brush. It is immaterial whether the socket is in the center of the plug for if it is 70 in the center of the brush, that is all that is necessary, for an evenly balanced brush results.

The socket 5 having been formed in the plug 3 after the brush has been mounted in 75 the knot, as above described, all that remains to be done is to insert the handle 6 in the socket, and secure the handle in place by means of a pin 7.

80 It will be apparent from the foregoing description that I have devised an extremely simple method of manufacturing brushes of this type; and it will also be apparent that there is a great saving of time, labor, and material in the practice of the invention. 85 By the old method, in common practice, the plug had to be removed, and this involved considerable time, and resulted in the loss of numerous brushes because of the loosening of the bristles during the removal of the 90 plug.

95 Further, while it has been suggested, in the patent to Hugh P. McMillan, cited above, to employ a permanent plug, yet in accordance with that idea the plug was a metal one and the handle receiving socket had to be formed in the plug prior to inserting the plug in the knot. It is obvious, accordingly, that to prevent the production of an unbalanced brush it was essential that the plug be very accurately centered with respect to the knot, and it is apparent to anyone skilled in the art that this is a difficult thing to do. In the present invention the time and labor involved for centering the 100 plug with respect to the knot is entirely eliminated; and applicant employs a wooden plug and provides a socket in the plug after the brush has been formed and merely centers this socket with respect to the brush instead of attempting to center the plug with 105 respect to the brush.

110 Having fully described the invention, what I claim as new and desire to secure by Letters Patent is:

1. The method of manufacturing brushes which comprises forming stock into a bunch and treating it with rubber solution to form a knot, inserting a plug in the knot, vulcanizing the rubber, forming a handle attaching means in the plug while in the knot, and attaching a handle to the handle attaching means.

2. The method of manufacturing brushes which includes forming stock into a bunch and treating it with a rubber solution to form a knot, inserting a plug in the knot, vulcanizing the rubber, providing the plug with handle attaching means while in the knot centered with relation to the brush 130

rather than to the plug, and attaching a handle to the attaching means.

3. The method of manufacturing brushes which includes forming stock into a bunch and treating it with a rubber solution to form a knot, inserting a plug in the knot, the top of the knot and the top of the plug

being in substantially the same plane, vulcanizing the rubber, forming a handle attaching means in the plug while in the knot, ¹⁰ the handle attaching means being centered with relation to the brush, and attaching a handle to the handle attaching means.

HUGH P. McMILLAN.
